UNITED STATES PATENT OFFICE.

CLAUDE AROUD FLEETWOOD AND WILLIAM H. LYSINGER, OF FORT DODGE, IOWA, AS
SIGNORS TO McLAUGHLIN COAL REDUCTION COMPANY, OF DECATUR, ILLINOIS, A
CORPORATION OF SOUTH DAKOTA.

FUEL FEEDER.

Application filed June 4, 1927. Serial No. 196,525.

This invention relates to mechanical stoking means and provides an apparatus whereby atomized fuel, such as coal, may be combined with air and gradually fed to the 5 fire box of a furnace in a manner to assure practically perfect combustion free from smoke and unconsumed gases.

The invention supplies a mechanism which assures a positive feed of the atomized coal 10 and a spreading thereof to produce a mixture which, when injected into the fire box burns with an intense flame free from the giving off of unconsumed particles, thereby conserving fuel and obviating smoke and the 15 waste of gases.

The invention contemplates an apparatus including a hopper for containing a quantity of the atomized coal, an agitator for insuring a positive feeding of the fuel, a cut off 20 for regulating the discharge of the fuel, a mixing chamber, means for delivering the atomized coal to the mixing chamber in a spread-out condition, means for circulating a regulated amount of air through the mixing 25 chamber to combine with the atomized coal, and means for forcing the fuel mixture into the air box of a furnace, all as will appear more fully in the subjoined description.

While the drawings illustrate a preferred 30 embodiment of the invention, it is to be understood that in adapting the means to meet specific needs and requirements the design may be varied and such other changes in the minor details of construction may be resorted 35 to within the scope of the invention as claimed, without departing from the spirit thereof.

For a full understanding of the invention 40 and the merits thereof, reference is to be had to the following description and the drawings hereto attached, in which,—

Figure 1 is a front view of a fuel feeding mechanism embodying the invention.

Figure 2 is a side view of the feeder.

45 Figure 3 is an enlarged sectional detail of the mixing chamber, spout, agitator and parts intimately associated therewith.

Figure 4 is a detail sectional view on the line 4—4 of Figure 3.

50 Figure 5 is a plan sectional view on the line 5—5 of Figure 3.

Corresponding and like parts are referred to in the following description and desig-

nated in the several views of the drawings by like reference characters.

The apparatus includes a hopper 1 for containing the atomized coal in bulk. The lower portion of the hopper 1 tapers and connects with a box 2, the walls of which incline in opposite directions, as shown most 55 clearly in Figure 4. A discharge opening 3 is formed in the bottom of the box 2 and is controlled by means of a cut-off 4 which is adjusted by means of a screw 5. The delivery opening 3 terminates a short distance 60 from the end walls of the box 2, thereby leaving a ledge 6 at each end of the discharge opening. An agitator is located within the bottom portion of the box 2, and comprises a shaft 7, a drum 8, and teeth 9 studding the 65 drum. The shaft 7 is mounted in bearings at opposite ends of the box 2. A short spiral or helical flight 10 is provided at each end of the drum 8 and serves to move the fuel from the ledges 6 towards the discharge 70 opening 3. A pulley 11 fast to an end of the shaft 7 is connected by means of a drive belt to a pulley fast to the shaft 12 of an 75 electric motor 13. The agitator is driven at a relatively slow speed.

The numeral 14 designates a mixing chamber which is extended at each end to form in effect a pipe through which air is positively circulated. A cut off 15 at the receiving end of the pipe regulates the admission of air 85 thereto. The casing of a fan blower 16 is connected to an extension of the mixing chamber 14 and is driven by means of the motor 13. A nozzle 17 connected with the casing of the fan blower is adapted to deliver the fuel mixture into the fire box, not shown, of a furnace. A spout 18 connects the box 2 with the mixing chamber. An opening or slot 19 is formed in the top side 90 of the mixing chamber 14 and has a spiral or helical arrangement, whereby to deliver the atomized coal into the mixing chamber in a spread out condition to insure every part being subjected to the current of air flowing through the mixing chamber, with 95 the result that the air and atomized fuel are thoroughly mixed. Plates 20 disposed within the spout 18 connect at their upper edges with the sides of the spout and are partly twisted towards their lower ends to conform 100 to the sides of the helical slot or opening 105

19, so as to direct the atomized coal through the opening 19 without offering any part for the fuel to lodge upon.

In the practical operation of the invention the atomized coal is supplied to the hopper 1, and the cut-offs 4 and 15 are adjusted to regulate the discharge of the fuel and supply of air. When the motor 3 is running the agitator and the fan blower are driven, thereby assuring a positive discharge of fuel and a supply of air to mix with the fuel, the mixture being drawn into the blower and forced thereby through the nozzle 17 into the fire box, not shown, where combustion takes place, as will be readily understood. The nozzle 17 may be arranged in any convenient position best adapted to location and conditions.

Having thus described the invention, we claim:

1. In a fuel feeder, a mixing chamber having a helically arranged opening in a side for the introduction of atomized coal into the mixing chamber, and means for circulating air through the mixing chamber to combine with the atomized coal to produce a fuel mixture.
2. In a fuel feeder, a mixing chamber, a hopper having a discharge opening in its bottom and a ledge at each end of the discharge opening, and an agitator within the bottom portion of the hopper and comprising a rotary member having projecting elements to insure a positive discharge of the material from the hopper and having helical flights to operate over the said ledges and prevent the accumulation of the material thereon.
3. A fuel feeder comprising a hopper, a rotary agitator within the bottom of the

hopper, a mixing chamber having a helical opening in a side, plates spread apart at their upper ends and gradually twisted towards their lower ends which connect with opposite sides of the helical opening in the 45 side of the mixing chamber, and means for circulating air through the mixing chamber for combining with the atomized coal to produce a fuel mixture.

4. A fuel feeder comprising a hopper, an 50 agitator in the bottom thereof, a mixing chamber having a helical opening in a side, plates connecting at their lower ends with opposite sides of the helical opening and gradually flaring towards their upper ends, 55 and twisted throughout their length, a cut-off for regulating the discharge from the hopper, a cut-off for regulating the admission of air to the mixing chamber, and means for circulating air through the mix- 60 ing chamber to combine with the fuel.

5. In fuel feeder, a hopper, a rotary agitator in the bottom thereof, a mixing chamber having a helical opening in a side thereof, a spout between the hopper and mixing chamber, plates within the spout having their upper ends in contact with opposite walls of the spout and their lower ends conforming to and in contact with opposite sides of the said helical opening, 70 said plates being twisted throughout their length, and a fan blower for positively circulating air through the mixing chamber and having a nozzle for the delivery of the fuel mixture to the required point of use. 75

In testimony whereof we affix our signatures.

CLAUDE AROUD FLEETWOOD. [L.S.]
WILLIAM H. LYSINGER. [L.S.]
